FIG. 1.

下口。乙。

A technical line drawing of a mechanical part, likely a bearing housing. It features a central vertical shaft or housing with a threaded top section labeled '59' and '15'. A cylindrical component labeled '57' is attached to the top. A rectangular block labeled '55' is positioned to the right. On the left, a vertical slot is labeled '29'. A horizontal slot on the right is labeled '28'. A horizontal slot on the left is labeled '30'. A horizontal slot on the right is labeled '33'. At the bottom, a horizontal slot is labeled '32' on the left and '31' on the right. A small vertical slot on the right is labeled '13'.

COPYING MACHINE FOR ENGRAVING
JEWELRY RINGS

Gerhard Gustav Gruettner and Rudy Charles Stiefel, New York, N. Y., assignors, by mesne assignments, to New Hermes Ring Engraving Corp., New York, N. Y., a corporation of New York

Application May 7, 1947, Serial No. 746,508

7 Claims. (Cl. 33—24)

1

The object of our invention is a copying machine for engraving letters, etc., into the inside of jewelry rings, such machine using a universally movable pantograph lever which carries a tracer for the pattern at or near one end and an engraving tool near the other end.

The workpiece, i. e. the ring, is held in a rotatable chuck.

Means are provided for causing a relative motion of approach and removal between said tool and said chuck to cause or interrupt engagement of said tool and said ring.

Means are also provided for indexing said chuck to secure the desired spacing between individual letters.

It is an object of our invention to construct such a machine in such a way that it can be reliably operated by unskilled workers.

With this aim in view it is particularly an object of our invention to make provisions for automatically actuating said indexing means during actuation of said relative motion means. Thus a reliable automatic letter spacing is secured and spoiling of workpieces by careless or unskilled workers is avoided.

Other features and advantages of our invention will become apparent from the following specification in connection with the accompanying drawings showing a preferred embodiment of our invention by way of example.

In the drawings is:

Figure 1 a front view of the machine with parts broken away to show details;

Figure 2 a side view of Figure 1;

Figure 3 is a perspective view of part of the machine on a larger scale at the end of the letter spacing operation;

Figure 4 a front elevation of the chuck and indexing means at the beginning of the letter spacing operation;

Figure 5 a side view of part of the drive for the chuck means shown in Figure 4;

Figure 6 a side view of the chuck means shown in Figure 4, the indexing means being omitted;

Figure 7 a front view of the drive for the chuck jaws, one jaw only being shown;

Figure 8 a section of the line 8—8 of Figure 7.

In the upright frame or stand 1 the pantograph lever 2 is mounted for universal swinging motion by means of the axles 3 and 4 at right angles to one another.

2

This lever has substantially the form of the letter E, having on its body an upper substantially horizontal arm 5 receiving said axles, therebeneath a second arm 6 carrying the engraving tool 7 and, on the lower end, a third arm 8 carrying the tracer or stylus 9.

The point of the tool 7, which is not rotated for cutting but acts as an engraving needle, has the known form of a pyramid with three or 10 more sides thus presenting cutting breasts all around to the workpiece.

The tracer 9 is slightly movable vertically in the arm 8 for permitting engagement of the tracer with and disengagement from the pattern letter 10 of the alphabet cut or engraved into the pattern carrier 11.

The workpiece, i. e. the ring 12 is held clamped by chuck means, to be described later more detailedly, on a plate or side 13 slidable vertically 20 in guide grooves 14 of the frame 1.

Here it is sufficient to say that the ring is held by three chuck jaws 15.

For moving the slide 13 up and down a control lever 16 provided with a handle or finger piece 17 is swingable with its axle or shaft 18 which is mounted in the frame 1. The lever 16 is a bell crank lever having a lateral arm 19. Through this arm extends a reduced end part 20 of a connecting rod or pitman 21. Between a shoulder 22 of the pitman and the arm 19 a coil spring or compression spring 23 is interposed so as to apply resilient pressure to the work to be engraved.

The upper end of the pitman 21 engages a 35 pin 24 on the outer end of an elbow lever consisting of the arms 25 and 26 and swingable on the pivot 27 on the slide 13.

The jaws 15 are mounted on slides 28 slidable in radial slots 29 of a ratchet wheel 30.

40 Each slide 28 has a pin 31 directed into sliding engagement with a spiral groove 32 cut into a gear wheel 33.

Gear wheel 33 is rotatable relatively to the ratchet-wheel by means of a knob 34 and intermediate gear wheel 35 meshing with said gear wheel 33.

Clockwise movement of gear wheel 33 moves the jaws inward along the ratchet-wheel 30 to clamp the ring 12.

50 The ratchet-wheel 30 with the chuck comprising the jaws 15 and assembly therefor and ring 12 is indexable, for letter spacing, by means

of a pawl 36 swingable on a pivot 37 of the lever arm 26 and urged by a spring (not shown) to engagement with the ratchet.

The idle counter-clockwise stroke of the pawl 36 is limited by one of three stepped shoulders 38, 39, 40 of an abutment lever 41 adjustable around a pivot 42 on the slide 13 for predetermining the amount of letter spacing. The lever 41 is adjusted by means of knob 43 (Figure 3) and is held in adjusted position by a spring pawl 44 engaging into teeth 45 of the lever 41. As shown in Figures 3 and 4 the shoulder 40 for the largest letter spacing is active.

Upon depression of the handle 17 and lever 16 by the left hand of the operator pitman 21 rises and turns elbow lever 25, 26 clockwise. Thereby the ratchet wheel 30 with the ring 12 are indexed an amount corresponding to the desired letter spacing.

A spring pawl 46 prevents backward rotation of the ratchet-wheel 30.

A stationary stop 47 on the slide 13 arrests the clockwise movement of the pawl 36 and presses the pawl firmly into the teeth of the ratchet. Hence continued depression of the handle 17 lifts the slide 13 bodily relatively to guides 14 and presses the inside of the ring 12 carried by the jaws 15 against the point of the tool 7 carried by the arm 6.

The operator then grasps with his right hand the knob 48 of the tracer and traces the desired pattern letter.

This letter is engraved on a reduced scale into the ring 12 by the tool 7.

The pattern carrier 11 is a disk indexable around a stationary pivot 49 and provided with a detent notch 50 opposite each letter of the alphabet. A slide lock 51 (Figure 3) is provided for locking the pattern carrier 11 in the indexed position for the letter to be engraved and has a slot 510 by means of which it is guided on a stationary pin 511. A coil spring 52 pulls the pointed end 53 of the lock 51 into engagement with the detent notch 50 at the selected position of the pattern carrier 11 thus holding the latter locked during engraving. When, however, the lever 16 and shaft 18 swing back counter-clockwise as viewed in Figure 3 a pin 54 of the shaft 18 strikes a nose 55 of the lock 51 and withdraws the point 53 from the notch 50. In this condition the disk 11 can be freely rotated for indexing to the desired letter.

From the above it will be seen that the lever 16 has three important functions viz.:

1. Indexing the ring for letter spacing;
2. Moving the ring into engagement with the tool;
3. Controlling the locking of the pattern carrier.

As shown in Figure 4 at least one of the jaws 15 has at least two of its sides provided with differently shaped recesses or faces. One side, e. g., has a flat face 55', the next side has a slightly curved, concave recess 56, the next has an angular recess 57, and the next a curved recess 58 of a smaller radius than the other curved recess. The jaws can be turned around pivots 59 for bringing any of these sides inwards to face the ring 12, thus making possible the firm clamping of rings of many different regular and irregular sizes and shapes.

What we claim is:

1. A copying engraving machine for jewelry rings comprising, in combination, a frame, a pantograph lever mounted universally movable

on said frame, a tracer tool holder mounted on said lever near the free end thereof, an engraving tool holder mounted on said lever near the other end thereof, a pattern carrier located near said tracer, a ring holding chuck mounted on said frame, means for peripherally indexing said chuck, means for causing a relative motion of approach and removal between said tool and said chuck, and single control means for actuating said first mentioned means and said second mentioned means successively.

2. A machine as claimed in claim 1 in which the pattern carrier is indexable, a lock is provided for locking said carrier in its indexed position, and said control means is a control lever mounted on said frame which is combined with means for controlling in addition to said means for relative motion and said indexing means of the chuck, a tilting member for the operation of said lock.

3. A machine as claimed in claim 1 in which said chuck has jaws at least one of which is rotatably adjustable around an axis parallel to the axis of the chuck and has at least two differently radially dimensioned sides for accommodating differently shaped rings by rotationally positioning at least one of said jaws.

4. A copying engraving machine for engraving rings comprising, in combination, a standard, a base for said standard, a pendulum lever having a universal pivotal support extending from the upper portion of said standard to adjacent the base, an arm for holding an engraving tool adjacent the upper support for said lever, means for holding a tracing tool adjacent the lower end of said lever for tracing from the pattern supported adjacent the base whereby a magnified movement of the tracing arm will move the engraving tool within limits of the ring to be engraved, a slide on said standard slideable vertically of the standard, a chuck rotatably mounted on said slide, indexing means for said chuck, a connector link for said slide to move said chuck and engraving tool relative to each other and a single control lever for operating said slide and indexing means for said chuck.

5. A copying engraving machine for engraving rings comprising, in combination, a standard, a base for said standard, a pendulum lever having a universal pivotal support extending from adjacent the upper portion of said standard to the base, an arm for holding an engraving tool adjacent the upper support for said lever, means for holding a tracing tool adjacent the lower end of said lever for tracing from the pattern supported adjacent the base whereby a magnified movement of the tracing arm will move the engraving tool within limits of the ring to be engraved, a slide on said standard slideable vertically of the standard, a chuck on said slide, indexing means for said chuck, a connector link for said slide to move said chuck and engraving tool relatively to each other and a single control lever for operating said slide and indexing means for said chuck, a pattern carrier on said base, detent means for said pattern carrier and detent control means operable by said single means.

6. A machine as claimed in claim 1 in which a slide is slidably mounted on said frame, a ratchet wheel is rotatably mounted on said slide, said chuck being mounted on said ratchet wheel for movement therewith, in which a pawl is mounted on said slide in peripheral engagement with said ratchet wheel, and in which said control means

includes a control lever mounted on the frame and having a connection to said pawl, said pawl being adapted to index said ratchet wheel during the first part of the movement of said control lever, and a stop is mounted on said slide and adapted to arrest the indexing movement of said pawl and to press the latter firmly against said ratchet wheel and thereby cause said relative motion by the second part of said movement.

7. A copying engraving machine for engraving on the interior surface of rings comprising, in combination, a frame, a pendulum lever having a universal pivotal support thereon, an arm for holding an engraving tool and an arm for tracing, each of which arms is mounted on said lever whereby a movement of the tracing arm will move the arm for the engraving tool within limits of the ring, a ring holding chuck within which said tool holding arm may be moved, a slide for said chuck slideable on said frame, indexing means for said chuck on said slide, and a single

control lever having a connection to said slide to move it to and from the tool holding arm in one range of movement and to index said chuck in another range of movement.
